AMBULANCE, OR SIMILAR VEHICLE

Gaylord W. Jones, 1121 E. Chevy Chase Drive,
Glendale, Calif.

Filed Aug. 28, 1962, Ser. No. 71,484

Term of patent 14 years

(Cl. D90—8)

The appearance of the side opposite to that shown in FIGURE 1 is substantially the same as that of the side illustrated.

The dominant features of my design reside in the portions shown by full lines.

I claim:

The ornamental design for an ambulance, or similar vehicle, as shown and described.
